TYPEWRITING MACHINE

Jesse A. B. Smith, Stamford, Conn., assignor to
 Underwood Elliott Fisher Company, New York,
 N. Y., a corporation of Delaware

Application December 21, 1935, Serial No. 55,503

4 Claims. (Cl. 197—103)

This invention relates to the keys of type-writing machines.

This invention discloses a very light, compact, fabricated key having a metal key-cup, secured to the key-lever, and an annular metal cap, struck up of thin metal, removably secured to the key-cup; said cap having a comparatively narrow, inwardly turned brim by means of which a preferably multi-ply character-disk is secured in position in such manner as to have an unsupported central portion.

In one embodiment of the invention, a character-bearing disk rests, entirely within the key-cup, on a flat-topped annular ring struck out of fibre or similar material. Overlying the character-bearing disk, a protective contact disk of hard, transparent Celluloid is placed, having a diameter equal to the outside diameter of the key-cup. The disk rests on the edge of the key-cup.

The metal cap is formed with a narrow, inwardly turned brim, which pinches the Celluloid disk tightly against the edge of the key-cup, and serves frictionally to hold the character-bearing disk in position, preventing its accidental rotation in use.

The character-disk is housed completely within the key-cup, and is not subjected to sharp bending. It can therefore be made of very inexpensive materials, such as stiff, heavy paper, etc.

The contact surface of the key is normally flat, but there is an unsupported or partially supported central area, and the yieldable contact-disk and character-disk form a cushion-like construction, which may yield slightly into the opening of the annular support, on being struck.

The annular flange or brim of the key-cap is very narrow, it being necessary only to extend over the edge of the key-cup. A large effective contact area is thus provided, making it possible, if desired, to reduce the overall diameter of each key without reducing the size of the character, or obscuring the operator's view of it. Such a reduction in key-diameter has the very desirable effect of increasing the finger-space or "well" between keys.

The key-caps have suitable ears or lugs arranged to be clasped beneath the key-cup when the key is assembled. Such assembly may be formed in a suitable press and sufficient pressure used to integrate the component parts into a tightly assembled unit.

During the pendency of my application Serial No. 698,063, filed November 15, 1933, (now Patent

No. 2,059,615) there was a requirement for division of certain of the subject matter contained in the present application as filed. Further division having been required, said subject matter is now contained in my co-pending application Serial No. 195,717, filed March 14, 1938.

Other features and advantages will hereinafter appear.

In the accompanying drawing—

Figure 1 is a perspective of a portion of a typewriter-key-bar with a key mounted thereon.

Figure 2 is a sectional view of the key construction, illustrating the concavity of the central area due to finger pressure.

Figure 3 is a sectional view of a slightly modified form of Figure 2.

Figure 4 is a detailed perspective of the disassembled key of Figures 1, 2 and 3.

Figure 5 is a representation of the key of Figure 3, showing the central area flexing under finger pressure.

Referring to Figures 1 and 4, 20 represents a typewriter-key-bar having an upwardly extending stem 21. A key-cup 22 is formed with a rectangular socket 23 to engage the stem tightly and has a circular base 24 and an upwardly extending rim 25, forming the cup.

An annular ring 26, Figure 4, which may be punched out of vulcanized fibre or other suitable material is formed to fit snugly within the key-cup on the bottom thereof, and forms a base for a character-bearing disk 27 on which is printed a character 28. The width of the ring 26 is sufficient to provide a substantial supporting surface for the disk 27, as illustrated in Figure 2, and its height, plus the thickness of the disk, is preferably equal to, or slightly greater than, the depth of the key-cup.

A protective disk 29 of thin, hard, transparent material, such as Celluloid, having a diameter equal to the outside diameter of the key-cup 22, is formed to overlie the character-disk 27 and serve as a protective element therefor.

A cap 30, which is formed to slidably engage the sides of the key-cup 22 with a tight fit, is a thin, annular metal band with a narrow inwardly turned brim or flange 31 and a plurality of downwardly extending ears or lugs 32.

After the annular ring 26, the character-disk 27 and the transparent disk 29 are assembled as shown in Figure 3, the assembly is integrated by slipping the cap 30 over the key-cup, pressing the brim 31 downward to pinch the disk 29 tightly against the edge of the cup, and bending the ears 32 inwardly beneath the key-cup. Rotation

of the protective disk 29 is prevented by the frictional engagement with the edge of the cup; the rotation of the character-disk 27 is likewise prevented by the frictional contact with the disk 29,
5 the inner wall of the key-cup, and the surface of the annular ring 26.

The assembled key has a normally planar contact surface, as indicated in Figure 3. The brim 31 is not flush with the surface, but as it projects
10 above it only slightly more than the thickness of the metal forming the brim, the key is much less punishing to the fingers of the operator than the usual high rim, glass topped, keys.

The contact surface of the key, being two-ply,
15 flexible, and with an unsupported central area, yields slightly under the pressure of the operator's finger as shown in Figure 5, cushioning the impact. In Figures 3 and 5, the character-disk 27 is shown of comparatively heavy stock, and the
20 annular ring 26 is narrower, giving less direct support to said disk. With this type of annular ring, the disk 27 may preferably be made of Celluloid, treated fabric, or similar material.

In the form shown in Figure 2, the disk 27 may
25 be of stiff paper, or similar material, as the annular ring 26 receives the greater force of the blow, and the central portion therefore concaves less than in the form shown in Figure 5.

Variations may be resorted to within the
30 scope of the invention, and portions of the improvements may be used without others.

Having thus described my invention, I claim:

1. A key for use with a typewriter, comprising in combination, a circular-edge cup, said cup
35 having provision for mounting on a key-lever, a circular composite key-disk including a character bearing disk united to a circular transparent disk, said transparent disk projecting beyond the border of the character-bearing disk, to form an
40 annular brim portion of the composite disk, annular means within said cup underlying said character disk for supporting the same at its border only, said brim resting upon the circular edge of said cup, and a removable annular metal cap
45 fitting on, and pinching said brim down upon the edge of, said cup to clamp the same against accidental rotation with respect to said cup.

2. A key for use with a typewriter, comprising

the combination of a cup having provision for mounting on a key-lever, a flat-topped annular support within said cup and resting on the base thereof, a resilient character-bearing disk supported on said annular support within said cup,
5 a resilient transparent protective element of diameter equal to the breadth of said cup resting on said character-disk and on the edge of said cup, and a metal band having an inturned brim arranged for clamping said protective element 10 against the edge of said cup.

3. A key for use with a typewriter, comprising the combination of a cup having provision for mounting on a key-lever, a flat-topped annular support within said cup and resting on the
15 base thereof, a resilient character-bearing disk supported on said annular support within said cup, a resilient transparent protective element of diameter equal to the breadth of said cup resting on said character-disk and on the edge of said
20 cup, and a metal band having an inturned brim arranged for clamping said protective element against the edge of said cup, the surface of said protective element remaining substantially planar.
25

4. A key for use with a typewriter, comprising in combination, a circular-edge cup, said cup having provision for mounting on a key-lever, a circular composite key-disk including a character-bearing disk united to a circular transparent disk,
30 said transparent disk projecting beyond the border of the character-bearing disk to form an annular brim portion of the composite disk, annular means within said cup underlying said character disk for supporting the same at its border
35 only, said brim resting upon the circular edge of said cup, and a removable annular metal cap fitting on, and pinching said brim down upon the edge of, said cup, to clamp the same against accidental rotation with respect to said cup, said composite disk being sufficiently flexible and sufficiently unsupported at its character-bearing area,
40 to flex when struck a staccato blow by the operator's finger, thereby cushioning the key stroke, said cap resisting the tendency of the disk, when
45 it is flexing, to pull off from the cup edge.

JESSE A. B. SMITH.
